MATERIAL HANDLING DEVICE

Filed Sept. 8, 1949

UNITED STATES PATENT OFFICE

2,597,374

MATERIAL HANDLING DEVICE

Clarence B. Richey, Royal Oak, Mich., assignor
to Dearborn Motors Corporation, Highland
Park, Mich., a corporation of Delaware

Application September 8, 1949, Serial No. 114,645

5 Claims. (Cl. 214—145)

1

This invention relates to an improved material handling device and particularly to a convertible manure fork and bucket for tractor mounted loaders.

In recent years, the large scale usage of tractors on farms has concurrently resulted in the utilization of ever-increasing numbers of tractor mounted loading devices which have been advantageously employed by the farmer to accomplish many of the arduous lifting or material handling tasks that are always present on a farm. Likewise, the use of tractor mounted loaders in industry and construction work has steadily increased. Particularly in its agricultural adaptations, the material engaging means on the loader takes one of two common forms, namely a manure fork and a bucket. A manure fork is very necessary in the handling of manure or similar entangled fibrous material, while a bucket type of container is the most desirable for handling of dirt, sand, gravel, or similar materials.

It is an object of this invention to provide a greatly improved material containing device which is unusually well-suited for agricultural loaders in that it may be conveniently converted from a manure fork into a bucket type of container.

Still another object of this invention is to provide an unusually rugged and strong material handling device for a loader which may, nevertheless, be economically manufactured by large quantity, low cost production methods.

Still another object of this invention is to provide an improved manure fork construction which will permit the fork tines to be readily assembled to or removed from the device but which will also provide an unusual degree of rigid support for such tines in their assembled position.

The specific nature of this invention, as well as other objects and advantages thereof, will become apparent to those skilled in the art from the following detailed description, taken in conjunction with the attached sheets of drawings on which, by way of preferred example only, is illustrated one embodiment of this invention:

On the drawings:

Figure 1 is a side elevational view of the material handling device embodying this invention, showing the device when assembled as a material bucket.

Figure 2 is a side elevational view of Figure 1.

Figure 3 is a vertical sectional view taken on the plane 3—3 of Figure 2.

2

Figure 4 is an enlarged scale partial sectional view taken on the plane 4—4 of Figure 3.

Figure 5 is an enlarged scale partial sectional view taken on the plane 5—5 of Figure 1.

5 As shown on the drawings:

While not limited thereto, the material handling device embodying this invention may be conveniently utilized on a tractor mounted loader of the type described in my co-pending application, Serial No. 114,646, filed concurrently herewith. In such loaders, the material handling device is generally pivotally mounted between a pair of spaced arms 10 which are suitably secured to the free end of the boom of the loader.

10 In addition, a pair of dumping control links 11 are conventionally provided on the loader.

A material handling device embodying this invention comprises a welded assembly of plate-like elements defining a base plate portion 12, upstanding opposed side wall portions 13, and an upstanding rear wall portion 14 mounted between side wall portions 13 and having a generally arcuate configuration, as viewed in vertical cross section. The bottom edge 14a of back wall 14 is welded to an intermediate portion of the base plate 12. The extreme top portion of back wall 14 is reversely bent as indicated at 14b to conform to the configuration of the top edges of the side plates 13. At aligned points on each of

20 the side walls 13, a U-shaped mounting bracket 15 is welded and the openings defined by brackets 15 respectively receive the ends of the arms 10 of the loader boom and are pivotally secured thereto by suitable pins 10a. A pair of ears 16 are welded to the top portion 14b of the back wall 14 respectively adjacent to side walls 13 and are suitably apertured to receive a pin 11a to pivotally connect the dumping links 11 thereto. By virtue of these connections to the tractor mounted

25 loader (not shown), the material handling device may be lifted, lowered, or dumped in conventional fashion.

30 An upstanding reinforcing plate 17 has its bottom end welded to the rear edge of the bottom plate 12 and its top edge welded to an intermediate portion of the back wall 14. In this manner, back wall 14 is effectively provided with two spaced apart wall portions in the vicinity of its juncture with the bottom plate 12. A plurality of transversely-spaced notches 14c (Fig. 4) are formed along the bottom edge of the back wall 14 and these notches are preferably of a non-circular configuration. A plurality of circular apertures 17a are formed in the reinforcing plate 17 in alignment respectively with the non-

35

40

45

circular apertures 14c. A plurality of forked tines 18 are employed which have the conventional pointed end portions 18a and throughout most of their length are of any conventional non-circular configuration, and preferably conform to the non-circular configuration of the apertures 14c so that they may be snugly inserted in such apertures. The other end 18b of each of the fork tines 18 is formed to a reduced area, circular cross section to permit such end portions to snugly project through the circular apertures 17a provided in the reinforcing plate 17. In this manner, displacement of the fork tines 18 relative to the device is prevented in the rearward direction by engagement of the shoulder 18c of the fork tines 18 with the front face of the reinforcing plate 17. Displacement of fork tines 18 in the direction to withdraw such tines from the device may be conveniently prevented by the insertion of cotter key 19 or similar detachable fastening element onto the projecting end portion 18b.

With the described construction, it is apparent that the fork tines 18 are detachably fastened to the material handling device and may be conveniently removed or reassembled at any time. Furthermore, the tines are secured on the device with an unusual degree of rigidity. Any tendency of the tines to turn is resisted by the cooperation of the non-circular apertures 14b with the non-circular cross section of the tines. Also, the fork tines 18 are well supported to resist any bending stresses produced thereupon during usual loading operations by virtue of having spaced point engagement with the device through the apertures 14b and 17a respectively and by resting on the bottom plate 12. It is obvious, therefore, that the described construction will function as a manure fork in a very satisfactory manner.

In the event that it is desired to convert the heretofore described manure fork into a material bucket type of handling device, a pair of extension side plates 20 are provided which are bolted to the side walls 13 respectively by bolts 21 in such manner as to form a continuation of the side walls 13. Also, an extension bottom plate 22 is provided having its lateral edges upturned as indicated at 22a to lie contiguous to the bottom portions of the extension side plates 20 and being bolted thereto by bolts 23. Projecting tabs 24 are welded to the rear edge of the extension bottom plate 22 and overlie the top face of base plate 12. Lastly, to provide support for the central portions of the extension bottom plate 22, a plurality of inverted U-shaped brackets 25 are welded to the top face of extension bottom plate 22 and define suitable recesses to provide sliding engagement with the projecting ends of the fork tines 18. Obviously, it is not necessary to provide a bracket 25 for each fork tine 18, and in the illustrated construction such a bracket is provided for four out of the seven fork tines.

When the assembly of the extension side plates 20 and the extension bottom plate 22 is completed, the material handling device is adequately converted into a material bucket and the pointed ends 18a of fork tine 18 still project to a limited degree beyond the front of the extension bottom plate 22 to assist in scarifying or loosening the material to be loaded into the bucket.

It is therefore apparent that this invention provides an unusually simple, rugged, yet economically manufacturable construction for a material handling device. The ease with which the described device may be converted from a manure

fork into a material bucket, or vice versa, coupled with the ease of removal or replacement of the fork tines, obviously makes the device very desirable for use on agricultural loaders. The interchangeable features have been accomplished without sacrificing in any manner the strength or rigidity of any of the critical components of the material handling device.

It will, of course, be understood that many details of construction may be varied through a wide range without departing from the principles of this invention and it is, therefore, not the purpose to limit the patent granted hereon otherwise than necessitated by the scope of the appended claims.

I claim:

1. A material handling device comprising plate-like elements secured together to define a bottom wall and an upstanding back wall, a reinforcing plate rigidly secured between said back wall and said bottom wall and having connection with said bottom wall in spaced relation to the connection of said back wall with said bottom wall, said back wall and said reinforcing plate having a plurality of transversely spaced, aligned apertures therein, the apertures in said back wall being of substantially different area than the respectively aligned apertures in said reinforcing plate, and a rod-like tine inserted through each aligned pair of said apertures, each of said tines being proportioned to snugly engage said apertures and having a shoulder defining the juncture between the larger and smaller area portions thereof, thereby limiting displacement of said tines relative to said device in one direction, and detachable fastening means engageable with said tines to limit displacement of said tines in the opposite direction.

2. A material handling device for loaders comprising a bottom wall element, an upstanding back wall element including two spaced apart wall portions rigidly secured at their bottom edges to said bottom wall, one of said wall portions having a plurality of transversely spaced, non-circular apertures therein, the other of said wall portions having a plurality of circular apertures therein respectively aligned with, and of smaller area than, said non-circular apertures, and a plurality of fork tines, each having a non-circular cross sectional portion snugly insertable in said non-circular apertures and a reduced area circular end portion insertable in said circular apertures, and means for detachably securing said fork tines against displacement relative to said fork portions.

3. The combination defined in claim 2 wherein said non-circular apertures constitute notches formed in the edges of said one wall portion contiguous to said back wall element, whereby said fork tines are supported by said bottom wall element.

4. A material handling device comprising plate-like members rigidly interconnected to define a bottom wall, an upstanding back wall and opposed side walls, a plurality of fork tines, means for securing said fork tines in transversely-spaced, forwardly projecting relationship to said bottom wall, whereby said device may function as a manure fork, a pair of side wall extension plates secured to said side walls, an extension bottom wall having upturned lateral edges respectively contiguous to said side wall plates, means for detachably securing said upturned lateral edges to said side wall extension plates, and a hollow

5

bracket on said extension bottom wall slidably receiving one of said fork tines to support the central portions of said extension bottom wall thereon, whereby said device may be converted to a material bucket.

5. A material handling device comprising a plate-like bottom wall and spaced side walls secured thereto, an upstanding back wall of arcuate configuration mounted between said side walls and rigidly secured at its bottom edge to an intermediate portion of said bottom wall, a reinforcing plate secured between an edge of said bottom wall and an intermediate portion of said back wall, said back wall and said reinforcing plate having a plurality of transversely-spaced, aligned apertures therein, the apertures in said back wall being of substantially different area than the respectively aligned apertures in said reinforcing plate, and a rod-like tine inserted through each aligned pair of said apertures, each

10

15
20

6

of said tines being proportioned to snugly engage said apertures and having a shoulder defining the juncture between the larger and smaller area portions thereof, thereby limiting displacement of said tines relative to said device in one direction, and detachable fastening means engageable with said tines to limit displacement of said tines in the opposite direction.
